(57) **CLAIM**

The ornamental design for an electronic viewfinder display screen with graphical user interface, as shown and described.

DESCRIPTION

FIG. 1 is a rear elevational view of a first image in a sequence for an electronic viewfinder display screen with graphical use interface showing a first embodiment of my new design;

FIG. 2 is an enlarged view of the graphical user interface of FIG. 1, shown separately for clarity of illustration;

FIG. 3 is a rear elevational view of a second image thereof; and,

FIG. 4 is an enlarged view of the graphical user interface of FIG. 3, shown separately for clarity of illustration.

The appearance of the transitional image sequentially transitions from the image shown in FIG. 1 to FIG. 3 and from FIG. 2 to FIG. 4. FIG. 2 is an enlarged view of FIG. 1 and FIG. 4 is an enlarged view of FIG. 3. The process or period in which one image transitions to another image forms no part of the claimed design.

The broken line showing of the digital camera is for the purpose of illustrating environment and forms no part of the claimed design. The broken line showing of elements on the display screen illustrate portions of the article and the portions of the screen display and the digital camera form no part of the claimed design.

1 Claim, 4 Drawing Sheets
